J. E. STEWART.
HOISTING APPARATUS.
APPLICATION FILED JAN. 18, 1917.

1,228,494.

Patented June 5, 1917.

John E. Stewart.
Inventor

By *Geo. Kimmel*,
Attorney

UNITED STATES PATENT OFFICE.

JOHN E. STEWART, OF OAKLAND, ILLINOIS.

HOISTING APPARATUS.

1,228,494.

Specification of Letters Patent.

Patented June 5, 1917.

Application filed January 18, 1917. Serial No. 143,099.

To all whom it may concern:

Be it known that I, JOHN E. STEWART, a citizen of the United States, and resident of Oakland, in the county of Coles and State 5 of Illinois, have invented certain new and useful Improvements in Hoisting Apparatus, of which the following is a specification.

The present invention relates to new and 10 useful improvements in hoisting apparatus.

The primary object of my invention is to provide a hoisting apparatus having means associated therewith to release the load carried when the same has been conveyed to the 15 desired location.

Another object of my invention is to provide a device of the character described having means associated therewith to convey articles of various sizes and weights without hindering the operation of my releasing 20 mechanism.

A further object of my invention is to provide an apparatus in which the parts thereof are closely assembled, and combined, 25 thereby taking a minimum amount of space.

Other improvements and novel details in the construction and arrangement of the various parts of the apparatus will be brought out more in detail in the description to follow, which, for a clear understanding of the invention, should be considered in connection with the accompanying drawings forming a part hereof, and wherein is disclosed, for the purpose of illustration, convenient 30 and satisfactory embodiments of the invention. It is to be noted, in this connection that minor changes in the construction and arrangement of the parts may be made without departing from the spirit of the invention or the principal operation of the various parts.

In the drawings:

Figure 1 is a perspective view of my invention as applied, and 45 Fig. 2 is a detail sectional view of the pivotal connection of the releasing rod and link member.

Referring now more particularly to the drawings wherein similar characters of reference designate like and corresponding parts throughout the various views, 50 10 designates a track for the carriage 11 having the common form of block 12 and tackle 13 associated therewith for raising and lowering the load carried as desired. The body

portion of my invention comprises a sheet metal band flexed intermediate its ends forming an enlarged loop 14 connected to the block 12 by means of the link member 15.

A pair of arms 16 extend in parallel relation from the said loop portion 14. A link member 17 and a rod 18 are pivotally connected to the free ends of the arms by means of a pin 19. An enlargement is formed on the said rod adjacent the connection to the arm 16 having a projection 20 extending therefrom for a purpose which will herein-after appear. A chain member 21 has one end thereof connected to the link 17 and the opposite end adapted for detachable association between said projection and portion 25. A flexible element 22 is connected to the rod 18 through the opening 23. Said flexible element is trained over a pulley 23' rotatably mounted between the said arms adjacent the enlarged loop 14.

In use when the bale of hay 24 as used in this case has been conveyed to the desired position over the track 10 the person operating the same pulls the flexible element 22 80 which raises the arm 18 as indicated in dotted lines thus releasing the chain from the projection 20, causing the load to be dropped.

From the above description taken in connection with the accompanying drawing, it 85 can easily be seen that I have provided a device that is simple in construction, containing but a few simple parts that can be cheaply manufactured and assembled and when assembled can be placed upon the 90 market and sold at a minimum cost.

Having thus fully described my invention what I claim as new and desire to secure by Letters Patent is:—

1. A hoisting device comprising a sheet 95 metal band flexed intermediate its ends forming a pair of parallel arms, a link member mounted between the ends of said arms, a rod having an opening in each end thereof and pivotally connected to the said arms between the ends of the link member, an enlargement formed on the end of said rod adjacent the end pivotally connected to said arms, a projection extending from said enlargement, a chain having one end connected 100 to the said link, the free end of the chain adapted for engagement with the said projection, a pulley wheel rotatably mounted between the said arms, a flexible element attached to the other opening in said rod and 110

trained over the said pulley for a purpose specified.

2. In a device of the class described a sheet metal band flexed intermediate its ends forming an enlarged loop, a pair of parallel arms extending from said loop, a rod, a link, said rod and link being pivotally connected to the free ends of said arms, a chain having

one end thereof connected to the said link, and the opposite end connected to the said rod and adapted to be released upon the raising of the said rod. 10

In testimony whereof, I affix my signature hereto.

JOHN E. STEWART.
